UNITED STATES PATENT OFFICE.

EMILE BERLINER, OF WASHINGTON, DISTRICT OF COLUMBIA.

TELEPHONE-TRANSMITTER.

SPECIFICATION forming part of Letters Patent No. 351,569, dated October 26, 1886.

Application filed August 17, 1885. Serial No. 174,609. (No model.)

To all whom it may concern:

Be it known that I, EMILE BERLINER, residing at Washington, in the District of Columbia, have invented certain Improvements 5 in Telephone-Transmitters, of which the following is a specification.

My invention relates to telephonic transmitters of that class in which a variation of contact produces a variation in the strength of 10 current. In my transmitter the variable contact to which the transmitting action is due occurs between two carbon plates or surfaces; and my improvements consist, first, in fixing 15 and employing one of the said surfaces as a diaphragm with a clamped edge, while the other, in the form of a carbon plate, rests by its own weight on the said carbon diaphragm; second, in diminishing the surface contact between said diaphragm and plate either by shaping them 20 convex and concave, respectively, or by shaping one plane and the other either convex or concave, or by perforating the contact-surface of the loose plate with numerous small holes to resemble net-work or a sieve, the object being 25 to facilitate the vibratory action and yet make contact between as large surfaces as possible.

I will now describe my invention by reference to the accompanying drawings. Figure 30 1 shows a cross-section of a transmitter wherein the contact-surfaces are concave and convex, respectively. Figs. 2, 3, 4, and 5 show modifications in the form of the contact-surfaces.

A and B are sections of a case for the contact-surfaces, preferably of insulating material, 35 as wood or hard rubber. The section A is recessed to receive a metal ring, D, upon which the carbon plate C is placed. The section of the case B is formed with a ring or flange to 40 enter the recess in A, and when placed in position is firmly fixed by screws *a*, thus holding the diaphragm-plate C firmly in its place. The plate E is laid upon C, so as to be loose or free 45 to move or vibrate. The surface of plate C is convex, that of plate E is concave, the arc of the latter being somewhat greater than that of the former. By this means I attain considerable surface contact, and consequently lower 50 resistance with a greater tendency to vibration than with any form yet employed. The circuit-terminals *y z* are connected, respectively, to the plate E and the metal ring D.

G is a mouth-piece, through which vocal utterance is directed upon the plate C.

In Fig. 2 the plate C is convex and plate E 55 is plane. In Fig. 3 E is convex and C is plane. In Fig. 4 C is convex and E has three concavities of such relative arrangement as to leave a circular rib, which engages with the fixed plate C. In Fig. 5 substantially the same end 60 is attained by perforating the plate E with numerous perforations.

In preparing the plates, I subject them to the heat and vapors of a hydrocarbon-gas retort, 65 as a retort where illuminating-gas is manufactured. The process is similar to the one described in my Patent No. 222,652, December 16, 1879, where carbon buttons or pins are used. The carbon plates so hardened can then be polished to suit the requirements of the transmitter. 70

I am aware that heretofore a telephone-transmitter has been devised wherein the variations in resistance were produced by varying the contact between two flat carbon plates or disks, 75 one of which rests loosely upon the other. The operation of such a transmitter, however, is found to be defective and irregular, owing in great part to the tendency of the plates to stick or adhere together. I have found in practice 80 that this difficulty may be avoided entirely, and great improvements effected in clearness and accuracy of transmission by forming one or both of the disks or plates with a curved contact-surface, as above described. I have 85 also found it to be an important improvement to clamp one of these plates or disks at its edges and employ it as a diaphragm. This construction is very advantageous on account of the pure vibration of such a diaphragm. 90

I am also aware that a transmitter has been heretofore devised having a metal diaphragm and a curved or dished plate of metal resting thereon. Such construction is not included in my invention, which, as already stated, has special reference to that type of transmitter where in the variations in strength of current are produced by varying the degree of contact between two carbon plates. 95

What I claim, and desire to secure by Letters Patent, is—

1. In a telephone-transmitter, the combination of two carbon plates forming the electrodes of a variable contact, one of said plates

resting by gravity upon the other, and one having a curved contact-surface, substantially as described.

2. In a battery-transmitter, the combination 5 of two carbon plates having curved contact-surfaces, the first of which is fixed in position and forms one electrode of a variable contact, the second of which forms the complementary electrode, rests by its gravity upon the first, 10 and is loose and free to vibrate.

3. In a battery-transmitter, the combination of two carbon plates forming the electrodes of a variable contact, the contact-surface of one being convex and that of the other concave.

15 4. A battery-transmitter consisting of the combination of two carbon plates having curved contact-surfaces forming the electrodes of a variable contact, the arc of the concavity of one being greater than the arc of the convexity of the other.

5. In a telephone-transmitter, the combination of a carbon diaphragm with fixed edge,

and a carbon plate resting loosely on said diaphragm.

6. In a telephone-transmitter, the combination 25 of two carbon plates forming the electrodes of a variable contact, one of said plates having a curved contact-surface.

7. The combination, in a telephone-transmitter, of an inclosing case in two sections, one of 30 which is recessed and contains a metal ring, a carbon plate firmly held in position upon said ring by the second section of the case, and a carbon plate resting upon the first plate by gravity, but otherwise free to vibrate. 35

In testimony whereof I have signed my name to this specification, in the presence of two subscribing witnesses, this 14th day of August, 1885.

EMILE BERLINER.
